UNITED STATES PATENT OFFICE.

JAMES J. ALLISON, OF NELSON, ILLINOIS.

BOTTLE-STOPPER.

SPECIFICATION forming part of Letters Patent No. 224,122, dated February 3, 1880.

Application filed June 20, 1879.

To all whom it may concern:

Be it known that I, JAMES J. ALLISON, of Nelson, Lee county, State of Illinois, have invented a new and Improved Bottle-Stopper, of 5 which the following is a specification.

The object of this invention is to furnish a self-closing bottle-stopper economical in construction and simple and efficient in operation.

10 The invention consists in a wire doubled to form a median loop or eye, and provided with elastic arms passing through stopper and having hook ends bent toward each other, as hereinafter described.

15 In the accompanying drawings, Figure 1 is a vertical section of a bottle neck and stopper, the latter in its closed position. Fig. 2 shows the same with the stopper opened to pour out the contents of the bottle. Fig. 3 is a top 20 view of the stopper. Fig. 4 represents the device for holding the stopper open when filling, and Fig. 5 is a modification of the wire arms. Fig. 6 is a side elevation, showing the modified form locked so that the stopper will pass into 25 the bottle.

Similar letters of reference indicate corresponding parts.

Referring to the drawings, A is the neck of the bottle, rising from the conical top B. C 30 is the rubber flange or disk, adapted to fit against the conical sides of B just below the neck. This rubber disk is held on the neck of a cast head, said neck connecting its two parts, a b, through which passes a wire having eye 35 or loop c in the middle, and spring-arms d d, which rise up through the neck and have their ends bent over toward each other.

When the bottle is filled the stopper presses 40 up under the neck, and the arms, springing apart over the top of the neck, draw the stopper up and hold it closed, as in Fig. 1. When the contents are to be emptied the arms are pressed down into the neck, carrying the

stopper down, and, being drawn together, one of the hooks catches the upright part of the 45 opposite arm, holding them together, so that the stopper will fall down in the bottle; but by inverting the latter the arms fall down through the neck, and can easily be separated again to hold the stopper up. 50

When filling the bottle the stop D is inserted in the faucet with the two wires f f extending down from it. These two wires pass down into the neck, furnishing a guide for the bottle, and also press the stopper down from its 55 seat, while the stopper, passing down to the top of the bottle, limits the movement of the wires in pressing down the stopper.

In Fig. 5 a modified form of the arms extending up from the stopper is shown. One 60 arm has a long vertical hook, g, in which the short horizontal hook on the other arm locks, as shown in Fig. 6 of drawings. This is a preferable style for certain kinds of bottles.

In case the stopper falls into the bottle by 65 the breaking of the wires, or is caught there by their becoming unhooked, it can easily be withdrawn by inserting a hook in eye c.

Having thus described my invention, I claim as new and desire to secure by Letters Patent— 70

1. A wire doubled to form a median eye or loop, c, and provided with the elastic arms d d, the latter passed through stopper, and having hook ends bent toward each other, as 75 shown and described.

2. The hooks e e on arms d d, in combination therewith and the stopper, for the purpose of holding the arms together when the stopper is dropped into the bottle to wash the 80 same, substantially as described.

JAMES J. ALLISON.
